UNITED STATES PATENT OFFICE

HOWARD O. JENKINS, OF BALTIMORE, MARYLAND, ASSIGNOR TO FRANK R. BLAKE, OF BALTIMORE, MARYLAND

DESIGN FOR A RING

Application filed December 4, 1929. Serial No. 33,635. Term of patent 14 years.

To all whom it may concern:

Be it known that I, HOWARD O. JENKINS, a citizen of the United States, residing at Baltimore, in the State of Maryland, have invented a new, original, and ornamental Design for Rings, of which the following is a specification, reference being had to the accompanying drawing, forming part thereof.

Fig. 1 is a top plan view of a ring, showing my new design.

Fig. 2 is an end view of the ring, showing my new design.

Fig. 3 is an end view opposite the view shown in Fig. 2.

I claim:

The ornamental design for a ring, as shown.

HOWARD O. JENKINS.
